Inventor
Emil Moore

UNITED STATES PATENT OFFICE.

EMIL MOORE, OF CHICAGO, ILLINOIS.

MILK-CAN.

SPECIFICATION forming part of Letters Patent No. 358,468, dated March 1, 1887.

Application filed October 9, 1886. Serial No. 215,805. (No model.)

To all whom it may concern:

Be it known that I, EMIL MOORE, residing at Chicago, in the county of Cook and State of Illinois, and a citizen of the United States, 5 have invented a new and useful Improvement in Milk-Cans, of which the following is a full description, reference being had to the accompanying drawings, in which—

Figure 1 is a vertical section. Fig. 2 is an 10 under side view. Fig. 3 is an under side view with the ice-receptacle removed. Fig. 4 is a top view of the ice-receptacle removed from the can. Fig. 5 is an enlarged detail showing a device for locking the ice-receptacle in its 15 place in the can.

It is common to provide milk-cans with an 20 ice-receptacle. Heretofore such receptacles have been connected with the cover of the can, the cover and the ice-receptacle being removed 25 together whenever access to the can is desired.

The object of my invention is to provide a 30 milk-can with an improved receptacle for ice, and which need not be removed, except when ice is to be placed therein, which I accomplish by locating the ice-receptacle at the bottom of the can, as illustrated in the drawings, and hereinafter described.

That which I claim as new will be set forth 35 in the claims.

30 In the drawings, A represents a milk-can, the real bottom of which is *a*, and below which there is an extension or flange, *b*, which may be made in any known manner. The upper portion of the can and its cover are made as usual.

35 *B* is a chamber extending up into the can from the bottom, which chamber is open at its bottom, but is made tight elsewhere.

40 *C* is a receptacle for ice, of such diameter that it fits readily into the chamber *B*. This receptacle for ice is open at the top. *c* is the bottom of the ice-receptacle proper, which extends out beyond the vertical wall of the receptacle, forming a shoulder, *d*, which, when 45 the ice-receptacle is in place in the can, comes in contact with the under side of the bottom *a*.

45 *D* is a chamber or receptacle for the water formed by the waste of the ice, which receptacle *D* is connected with the bottom of the 50 ice-chamber. In fact, the bottom *c* of the ice-chamber forms the top of the water-receptacle *D*. There is an opening, *e*, in the bot-

tom *c*, through which water can flow into the chamber *D*. *f* is an outlet from the water-receptacle *D*, which may be closed by a plug, *g*; 55 and by removing the plug the water which has accumulated in the receptacle *D* can be drawn off.

h is a light spring, one end of which, as shown, is secured to the bottom of the water-receptacle. The other end of this spring is free and covers the opening or hole *e*, but not so tightly as to prevent the water from escaping from the ice-receptacle *C*. The object of this spring is to prevent the body of the water 65 which may have accumulated in the water-receptacle *D* from flowing into the ice-receptacle in case the can be turned upon its side.

i are wires over the opening *e*. These wires extend through the bottom *c* to the bottom 70 of the water-receptacle *D*. They serve the double purpose of strengthening the parts and protecting the opening *e*. *j j'* are two ears or lugs secured to the water-receptacle on a line with its top. 75

k k' are two metal holding-pieces. One end of each piece is soldered to the bottom of the can, and the other ends are bent down a little, so that the ears *j j'* can pass under. Each of the ears *j j'* is provided with a hole, *l*. The 80 outer ends of the strips of metal *k k'* are also provided with a hole, *m*, which registers with the hole *l*. *n* is a spring, one end of which is secured to the bottom *a* of the can. The other end is provided with a pin, *o*, adapted to enter the holes *m l*, for the purpose of holding the ice-receptacle in place in the can. *p* is a finger-piece at the free end of the spring *n*. 85

The ice and water receptacles can be removed together from the can by first disengaging the pin *o* from the ear and then turning the water-receptacle and ice-receptacle sufficiently to disengage the ears *j j'* from the metal pieces *k k'*. After ice has been placed in the ice-receptacle *C* it and the water-receptacle can be replaced, as shown in Fig. 1. I thus provide a milk-can with an ice-receptacle which need not be removed, except when it is necessary to place ice therein. 90 95

The ears or lugs *j j'* and the parts or holding-pieces *k k'* may all be made of malleable iron and secured in place by rivets. The ice and water receptacles may both be made of galvanized iron. The spring *h* may be se- 100

cured to the under side of the bottom *c* of the ice-receptacle, instead of to the bottom of the water-receptacle, as shown in the drawings.

5. What I claim as new, and desire to secure by Letters Patent, is—

1. The combination, with a milk-can having an open-bottomed chamber, *B*, extending up into the can from the can-bottom, of a detachable ice-receptacle, *C*, provided on its bottom with a lateral flange or shoulder, *d*, in contact with the can-bottom, said ice-receptacle being formed with vertical sides to fit closely in the lower end of the chamber *B*, substantially as described.

15 2. A milk-can provided with a chamber, *B*, open at the bottom, in combination with an ice-receptacle, *C*, fitting into said chamber and detachably secured to the can-bottom, and a

water-receptacle, *D*, to receive the drip from the ice, substantially as specified.

3. In combination with a milk-can provided with a chamber, *B*, holding-pieces *k* *k'*, and spring *n*, having pin *o*, an ice-receptacle, *C*, provided with a water-receptacle, *D*, and ears *j* *j'*, said holding-pieces and ears being provided with registering apertures, substantially as and for the purposes specified.

4. In combination with a milk-can, an ice-receptacle, *C*, and a water-receptacle, *D*, communicating with each other by means of an opening, and a spring, *h*, to control the opening, substantially as and for the purposes specified.

EMIL MOORE.
